UNITED STATES PATENT OFFICE

156,685

CASE FOR EXPOSURE METER OR SIMILAR ARTICLE

Nathan H. Weiss, New Brunswick, N. J., assignor to Louis Lefkowitz & Bro., Inc., New Brunswick, N. J., a corporation of New Jersey

Application December 9, 1947, Serial No. 143,065

Term of patent 3½ years

(Cl. D61—1)

To all whom it may concern:

Be it known that I, Nathan H. Weiss, a citizen of the United States, residing at Highland Park, New Brunswick, in the county of Middlesex and State of New Jersey, have invented a new, original, and ornamental Design for a Case for Exposure Meter or Similar Article, of which the following is a specification, reference being had to the accompanying drawing, forming part thereof.

In the drawing:

Fig. 1 is a top perspective view of a case for exposure meter showing my new design;

Fig. 2 is a bottom perspective view of the case; and

Fig. 3 is an opened up perspective view.

I claim:

The ornamental design for a case for exposure meter or similar article, as shown.

NATHAN H. WEISS.
